GEIGER-MUELLER COUNTER TUBE

Paul Burg Weisz, Swarthmore, Pa.

Application September 27, 1948, Serial No. 51,401

4 Claims. (Cl. 250—27.5)

1

This invention relates to improvements in Geiger-Mueller counter tubes and more specifically to new gas fillings for counter tubes to be operated as self-quenching Geiger-Mueller tubes.

Many types and designs of Geiger-Mueller tubes (hereafter referred to as GM-tubes) are known. Such tubes generally operate at voltages of around one-thousand volts and are filled with special gas mixtures, certain compositions of which will result in tubes having what is known as self-quenching operating properties. The particular gas fillings employed do not only determine whether a given tube can thus be operated as a self-quenching GM-tube but also determine very largely its qualities which can be measured by such major characteristics as the operating potential, nature of the counting "plateau," the "dead-time" and the temperature sensitivity of the tube. This invention is concerned with new and specific gas mixtures which when employed in GM-tubes of generally accepted designs will not only result in reliable self-quenching operation but will result in improved operating characteristics such as mentioned above, as compared to those possessed by GM-tubes employing presently known gas fillings.

A further object of this invention is to provide special gas mixtures which, besides offering improvements in the operation of GM-tubes, are easily prepared, stored and managed in large quantities in connection with the manufacture of such GM-tubes. This is a considerable improvement since presently known gas fillings are not easily handled when mixed in quantity, mainly because of the low natural vapor pressure which at least one of their components has at ordinary room temperatures.

The GM-tube is now a well-known instrument for the detection of radiations. Figure 1 shows a typical GM-tube, having a cylindrical vacuum-tight envelope 1 which contains an electrically conducting cylindrical electrode 2 which serves as a cathode, a thin coaxially suspended metal wire 3 which serves as an anode, and a gas filling which is introduced into the space 4 through a seal-off stub 5. The tube is essentially gas-filled type electronic discharge tube which is so designed that no discharge current flows between its electrodes 2 and 3 until an ionizing event such as produced by radiations takes place within the sensitive volume of the tube. In a properly designed GM-tube such an event is followed by the development of a brief electrical discharge through the gas space 4 which is measurable by

2

suitable electrical recording equipment, the latter being diagrammatically indicated by 6 when an operating voltage 7 is placed across the tube. Any ordinary combination of electrodes contained in a gas space will continue in a state of breakdown or electrical conduction through the gas space, once the operating voltage across it has been raised high enough so that a discharge has been initiated. In order that a discharge tube be capable of detecting individual ionization events, so that it can properly be designated as a GM-tube, it is necessary therefore that in the design means are provided to extinguish the discharge after it has been initiated and after it has manifested itself in a measurable current impulse following each individual ionization event. In the achievement of this end, namely the achievement of repetitive operation in the form of single electrical impulses rather than continuous electrical breakdown or even "trains" of repetitive pulses, lies the art of design and construction of tubes known as Geiger-Mueller tubes. The particular class of GM-tubes known as self-quenching tubes and to which this invention refers to is characterized by the fact that the repetitive extinction of each discharge is accomplished automatically by the tube itself and not by external artificial means of special circuitry which complicates their use and in fact limits the speed of counting of such non-self-quenching tubes. Furthermore, such operating conditions must prevail over reasonable ranges of operating voltages, temperatures and other operational variables, in order that a GM-tube may be a practical device.

When a tube of the design of a GM-tube is filled with any gas, an ionizing event will produce a current impulse whenever an electric potential is applied to the electrodes, and the magnitude of that impulse will increase rapidly with increasing electrode potential. At sufficiently high voltage, any such tube will give rise to impulses of a few millivolts up to, in some cases, the order of a volt. These are in a sense self-quenching since they do not result in extended electrical breakdown. However, the individual impulses are not equal in size but consist of a wide distribution of sizes. This type of operation is impractical for counting purposes. It can only be accomplished by the use of sensitive amplifiers with considerable amount of amplification. It is clear that for any finite sensitivity for such an amplifier those impulses of the pulse size distribution will not be counted which have an amplitude less than the minimum recordable

size. Any GM-tube has a range of operating voltages for which this type of operation prevails, namely below the "Geiger-threshold" which is the voltage at which distinct equalization of pulse-sizes and thus "Geiger counter action" is said to set in. An example for a gas filling which shows only such sub-Geiger-threshold action even with the highest applied voltages before breakdown occurs is methane. Methane with an inert gas as a major admixture will breakdown before any pulses of large size are attained, however methane alone will show sub-threshold action up to several thousands of volts at which some impulses may attain amplitudes as high as of the order of a volt. However, as said before, any gas filling will yield some range of operating voltage at which such unequalized more or less small impulses can be obtained. Nowadays, a sharp distinction is made between such operation and Geiger-counter action, and it will be understood that this invention deals with gas fillings for self-quenching operation above the Geiger threshold, yielding equalized impulses, and displaying a distinctly long counting plateau.

There are four important properties of self-quenching counters which can be measured in order to evaluate the relative qualities of such GM-tubes.

1. The "plateau" is the curve which demonstrates the variation of recorded pulse rate when only the operating voltage is varied. This quantity is usually measured by the slope of this curve over what is considered the operating range and is usually expressed by the ratio of the variation of pulse rate in percentage units which results when the operating voltage is varied by one-hundred volts and by the approximate length (in voltage units) of the relatively flat portion near the operating voltage.

2. The approximate "operating voltage" is an important property since it is often impractical and expensive to have to provide operating voltages of, say, 2000 volts or more. In general, it is nowadays considered most practical to operate GM-tubes at voltages of about 1000 volts or at lower voltages.

3. The "dead-time" defines the time which must elapse after the recording of each impulse before the tube is again sensitive for the recording of another ionization event. For a typical GM-tube as mentioned under (1) above, this dead-time may be about ninety micro-seconds. In order that GM-tubes be operable at higher counting rates without counting errors and losses due to this insensitive time, one strives to design tubes of shorter dead-times.

4. In some applications the temperature dependence of the above three characteristics is an important matter. It has been found that when the ambient temperature of the tube is lowered, a temperature is reached at which a drastic change in operating character occurs leading to a shift in operating voltage and at somewhat lower temperature in actual disappearance of the flat portion on the counting plateau, thus making the tube inoperable and worthless. This is an important consideration when the tubes are to be used under conditions of variable temperature such as in geological prospecting, out-of-door use or in some cases even in closed rooms which are not temperature controlled.

One of the most determining design factors to accomplish self-quenching type of operation

and good characteristics as defined by the above paragraphs (1) to (4) is the particular nature of the gas filling used in the tubes.

Typical gas fillings which have been used and are in use consist mainly of one of the inert gases such as argon and an admixture of certain organic vapors which are characteristic for the production of self-quenching action. Such vapors as have been used are: the vapors of ethyl alcohol, amyl acetate, ethyl ether, halogen-substituted hydrocarbons, such as ethylene dibromide, and a few metal-organic compounds such as tetramethyl lead.

The teachings of this invention are based on a study of the properties of GM-tubes filled with such known vapors as quenching gas components and a search for other gases and vapors showing improved characteristics and advantages in use.

Accordingly, it was found that the unsubstituted hydrocarbons containing only carbon and hydrogen in their molecules, and in particular those hydrocarbons characterized by having between two and eight carbon atoms per molecule, inclusively, are exceedingly well suitable as quenching components for gas fillings.

In the following part of this specification a comparison of the characteristics of these new quenching gases as compared to the gases employed in the present art will be made and examples given for the many specific gas mixtures tested together with their characteristics, and the various advantages of the new gas mixtures will be demonstrated.

GM-tubes of good quality can be made by using as a quenching component of the gas filling a constituent selected from the series of normal straight-chain hydrocarbons which is characterized by the formula C_nH_{2n+2} , with the carbon number n being a number between two and eight inclusively, in connection with another usually chemically inert gas of the type generally known to be usable as such non-quenching component in GM-tubes and in proportions generally customary for the non-quenching and quenching components of a GM-tube gas mixture.

For example, tubes of conventional design, having a cathode diameter of .5 inch and length of 7 inches and an anode wire diameter of .003 inch have been filled with 13.5 cm. of Hg pressure of argon and 1.5 cm. Hg pressure of various normal hydrocarbons from ethane to octane and the lowest operating voltage was measured. Figure 2 is a reproduction of the results thus obtained. It will be noted that the operating voltages all lie in a reasonable range.

The plateau characteristics were similar for all gases thus used; and in Figure 3 two typical examples are reproduced, namely for n-butane and n-hexane, and for comparison a standard ethyl alcohol and argon filling was prepared in the same GM-tube and the plateau characteristic obtained therewith is also reproduced on the same drawing for comparison. It will be obvious that the plateau curves obtained with the new gases are superior to that of the equivalent ethyl alcohol filled tube.

GM-tubes of equally good quality have been obtained by using the normal hydrocarbons as above but substituting other chemically inert gases besides argon, for which Figure 4 demonstrates, by way of example, the use of helium in place of argon under otherwise identical circumstances as in the measurements described in which argon was used, by showing the resulting operating voltages. The plateau characteristics

were again similar in all cases to the typical examples in Figure 3.

Furthermore, it was found that the substitution of the normal hydrocarbons by any of their isomeric forms having the same composition C_nH_{2n+2} did not appreciably effect the electrical operating characteristics. This finding was to be expected in line with scientific findings concerning the fact that the ionization potential of various isomers does not appreciably change with alteration of isomeric structure. Thus, identical results were obtained for the electrical operating characteristics for the following examples tested: n-butane and iso-butane, n-pentane and di-methyl-propane, n-octane and 1-1 di-methyl-hexane.

Furthermore, it was found that essentially identical results were obtained with the cyclic forms of the hydrocarbons having the composition C_nH_{2n} , as seen by identical results obtained from n-hexane and cyclo-hexane.

It was further found that the presence of a double carbon-carbon bond in the hydrocarbon molecule, such hydrocarbons being known as olefins and having the composition C_nH_{2n} , did not interfere with its qualities in producing good quenching characteristics, although the operating voltage for the olefins is generally somewhat lower than in case of its equivalent paraffin hydrocarbon compound, as seen by the following examples in Table I which were studied with the olefin and argon under conditions equivalent to the previous examples.

Table I

Compound	Lowest Operating Voltage
Ethane	
Ethylene	
Propane	
Propylene	
n-Butane	
Butene-1	
Butene-2	

It was found, however, that when using olefinic hydrocarbons as indicated the life-time of such tubes was somewhat unpredictable, and this limitation was thought to be caused by a tendency towards polymerization of such olefins caused by the action of the discharge. The use of the olefin hydrocarbons is not considered to be preferable to the use of the paraffin type hydrocarbons.

Now several advantages connected with the hydrocarbon gases as quenching components will be seen when other characteristics are compared.

The dead-time was measured for such hydrocarbons and for other customarily used quenching components, and a comparison can be made by comparing the results as tabulated in Table II.

Table II

Hydrocarbon	Dead-time
Ethane	42
Propane	53
Butane	60
n-Pentane	72
Neo-pentane	70
Hexane	75
Heptane	95
Ethylene	50
Ethyl alcohol	94
Tetramethyl lead	140
Amyl acetate	100
Ethylene dibromide	140

It is obvious that practically all the hydrocarbons result in short dead-times, and in particular the dead-times of the lighter hydrocarbons, ethane and propane, for example, are strikingly short and superior to equivalent standard type of gas fillings.

The property of tubes to fail at lower operating temperatures has been found to be connected with the fact that at a given low temperature part or all of the quenching gas component begins to remove itself from the gas space by condensation. The temperature at which this failure will set in will be the lower drop with lower boiling points of the pure quenching gas component.

It is easily observed that such known quenching vapors as alcohols, ethers, and halogenated hydrocarbons as well as organo-metal compounds as have been found useful as quenching gases in the past all have relatively high boiling points, while amongst the unsubstituted hydrocarbons many can be found with boiling points considerably lower.

As a result, such hydrocarbons will allow operation at considerably lower temperatures than all of the vapors known for otherwise equivalent conditions.

In Table III, boiling points are compared, and in Table IV the approximate temperatures are shown at which tubes actually begin to fail when using various quenching gases under the same conditions as in all the above examples.

Table III

Compound (old)	B. P.	Compound (new)	B. P.
Ethyl ether	°C. +34.6	Ethane	°C. -88.6
Ethyl alcohol	+78.4	Propane	-42.2
40 Volts	+110.0	n-Butane	-0.6
Ethylene dibromide	+131.5	Iso-butane	-10.0
Amyl acetate	+148.7	n-Pentane	+36.3
		Iso-pentane	+28.0
		Neo-pentane	+9.5
		n-Hexane	+69.0
		Cyclo-hexane	+80.0
		Ethylene	-103.9
		Propylene	-46.0

Table IV

Compound (old)	Approx. Temp. of Failure	Compound (new)	Approx. Temp. of Failure
Ethyl ether	°C. -40	Ethane	°C. below -78
Ethyl alcohol	+5	Propane	below -78
Amyl acetate	+35	n-Butane	-65
Ethylene dibromide	+25	Iso-butane	below -78
Tetramethyl lead	+15	Neo-pentane	below -30
		n-Hexane	-15
		Ethylene	below -78

60 The approximate temperatures of failure given in Table IV apply to the partial quenching gas pressure of 15 mm. (Hg) used in the above examples. When tubes are constructed with lower concentrations of the quenching components, the critical temperature of failure is lowered; and in fact in the case of amylic acetate and ethylene dibromide GM-tubes must be filled with their partial pressures being considerably below 15 mm. (Hg).

65 70 However, Table III and Table IV show how the new quenching gas components lead to lower critical temperatures than known types of quenching gas components under similar conditions.

75 According to this invention, the new type of

quenching gas component can be used in place of the types presently known in connection with customary non-self-quenching gas components such as argon, neon, helium, hydrogen and others, and in relative concentrations and total gas pressures generally acceptable for known quenching components.

However, it was found that such quenching gases as are presented by this invention can be used over wider ranges of relative concentration and total gas pressure than is the case of ethyl alcohol and other known gases, without seriously affecting the resulting operating qualities of tubes filled by their use.

While the optimum pressure ranges depend largely on the anode wire diameter, it was found that optimum operating characteristics were attained as follows:

(a) With anode wire diameters of approximately .008 inch or less, with partial pressures of the new quenching gases approximately equal to between one (1) and twenty-five (25) mm. (Hg) and total gas pressures of approximately between fifty mm. (Hg) and atmospheric pressure;

(b) With anode wire diameters of approximately .008 inch to .035 inch, with partial pressures of the new quenching gases approximately equal to between one-tenth (.1) and ten (10.0) mm. (Hg) and total gas pressures of approximately between fifty (50) mm. (Hg) and atmospheric pressure.

In particular, it was found that these new quenching gases are capable of yielding successful and high quality operation of GM-tubes when the total internal pressure is nearly as high or actually equal to the pressure of the external atmosphere. None of the quenching gases heretofore described have operated at total pressures approximating atmospheric pressure, and the new gases make such operation distinctly possible under operating conditions which are quite normal and customary for tubes which in the past have operated only at reduced pressures. In many cases of application of GM-tubes higher internal gas pressures lead to higher efficiencies of detection wherefore this property is to be considered an additional advantage.

There are many cases in which atmospheric pressure operation means a real improvement. For example when tubes are to be equipped with very small thickness windows for the detection of low energy radiations the minimum possible thickness is almost entirely dictated by the considerable pressure difference between the atmosphere and the tube interior. Such limitation virtually disappears when the new atmospheric gas fillings are used. Also, it is possible to fill such tubes without employing vacuum equipment otherwise required to obtain the fractional internal gas pressures.

It was found that in operating GM-tubes at essentially equal to atmospheric total internal gas pressures, certain of the hydrocarbon gases are to be preferred because of the low operating voltages which result when they are used in preference to others.

For such uses it was found that preferred gas mixtures were obtained by providing compositions which consisted of either a saturated or cyclic hydrocarbon with three to five carbon atoms, in connection with argon as the major gas component. The gases found to be preferred as hydrocarbon constituents for atmospheric pressure operation can be characterized therefore by

the formulae: C_2H_4 , C_3H_6 , C_3H_8 , C_4H_8 , C_4H_{10} , C_5H_{10} and C_5H_{12} . The optimum conditions were attained when the concentration of the hydrocarbon component was about .1% to 6% of the total gas mixture; when the GM-tube in which the gases were used had an anode diameter of about .008 inch or less. For larger anode diameters the optimum hydrocarbon concentration was found to be smaller. For anode diameters ranging from .008 inch to about .035 inch the best suitable hydrocarbon concentrations were found to range from .01% to 1.0% of the total gas pressure.

An important advantage can be derived from the use of most of the gases the use of which is taught by this invention in the processes connected with the preparation of the quenching gas mixtures, their storage, and their use when GM-tubes are to be constructed or manufactured.

It is well known that presently known quenching compounds are liquids at normal temperature and pressure and that therefore they exhibit a definitely limited vapor pressure at such temperatures at which they are handled. In the process of preparing the gas mixtures this must always be taken into account and presents limitations on procedure as well as on the total amount of a given gas mixture which can be prepared or stored in a reservoir of given volume.

For a given volume of a storage reservoir only little gas volume can be stored for any attempt to compress the mixture would lead to partial liquefaction of the quenching component, and in such a case the relative composition of the gases removed continuously changes with the amount of gases removed as well as with the temperature of the environment.

Now, because of the low boiling points demonstrated in Table III for the new quenching gases, it is possible to handle many of them such as ethane, propane, butane, neo-pentane, ethylene, propylene as gases in any mixing equipment.

Furthermore, some of them are readily compressed without danger of liquefaction by such factors which make the storage of large quantities of pre-mixed gas mixtures possible and economical.

For example, it is well known that n-butane will not be liquefied so long as its partial pressure in a compressed cylinder is less than about 15 p. s. i. Thus if it were desired to make and store a gas to be used as filling gas for self-quenching GM-tubes containing ultimately 1.0 cm. (Hg) of n-butane and 30 cm. (Hg) of argon when filled into the GM-tubes, i. e. at a ratio of one part butane to 30 parts of argon, it would be possible to make and store such a gas mixture in a pressurized cylinder at a total pressure of about 450 p. s. i. representing a gas volume of thirty times the cylinder volume when referred to standard conditions. Even larger quantities of mixture could be made and stored in case of isobutane, propane and other hydrocarbons with boiling points below that of n-butane under conditions otherwise equal.

While in all examples given the gas fillings were considered as consisting of two gaseous components, namely the quenching gas component and the non-quenching gas component, it must be understood that by all known principles the use of two or more gases known individually to have the desired quenching properties, as well as the use of two or more non-quenching gas components each being known to have the desired characteristics individually would be pos-

sible and leads to similar results as does the use of just two-component mixtures. The teachings of this invention are to be understood therefore to include the possibility of combining more than two components of such gases as it teaches to be applicable and usable in case of the described two-component mixtures.

I claim as my invention:

1. A gas mixture for the filling of Geiger-Mueller tubes for the purpose of providing such tubes with self-quenching properties with pulse equalization at substantially atmospheric internal gas pressure, consisting of a major and a minor component the former of which comprising at least one of the gases hydrogen, nitrogen, argon, neon, and helium, and the latter of which comprising at least one of the hydrocarbons selected from the group of compounds described by the chemical formulae C_nH_{2n+2} and C_nH_{2n} wherein the carbon number n be a number between two and eight inclusively, said hydrocarbon component making up from 0.1% to 6%, approximately, of the total gas pressure.

2. A gas mixture for the filling of Geiger-Mueller tubes for the purpose of providing such tubes with self-quenching properties with pulse equalization at substantially atmospheric internal gas pressure, consisting of argon and C_4H_{10} , and where the latter gas constitutes from 1% to 6%, approximately, of the total gas pressure.

3. A gas mixture for the filling of Geiger-Mueller tubes for the purpose of providing such tubes with self-quenching properties with pulse equalization at substantially atmospheric internal gas pressure, consisting of helium and C_4H_{10} , and where the latter gas constitutes from 1% to 6%, approximately, of the total gas pressure.

4. A gas mixture for the filling of Geiger-Mueller tubes for the purpose of providing such tubes with self-quenching properties with pulse equalization at substantially atmospheric internal gas pressure, consisting of argon and C_2H_4 , and where the latter gas constitutes from 1% to 6%, approximately, of the total gas pressure.
